(57) **CLAIM**

The ornamental design for a pond cover fastener, as shown and described.

DESCRIPTION

FIG. 1 is an upper right perspective view of a pond cover fastener;

FIG. 2 is a lower left perspective view of the pond cover fastener shown in FIG. 1;

FIG. 3 is a top view of the pond cover fastener shown in FIG. 1;

FIG. 4 is a bottom view of the pond cover fastener shown in FIG. 1;

FIG. 5 is a left side view of the pond cover fastener shown in FIG. 1;

FIG. 6 is a front view of the pond cover fastener shown in FIG. 1;

FIG. 7 is a rear view of the pond cover fastener shown in FIG. 1;

FIG. 8 is an upper perspective view of an alternative embodiment of the pond cover fastener;

FIG. 9 is an upper rear perspective view of the pond cover fastener shown in FIG. 8;

FIG. 10 is a top view of the pond cover fastener shown in FIG. 8;

FIG. 11 is a bottom view of the pond cover fastener shown in FIG. 8;

FIG. 12 is a left side view of the pond cover fastener shown in FIG. 8;

FIG. 13 is a front view of the pond cover fastener shown in FIG. 8; and,

FIG. 14 is a rear view of the pond cover fastener shown in FIG. 8.
